[57] CLAIM

The ornamental design for a water filter, as shown and described.

DESCRIPTION

FIG. 1 is a front isometric view of a water filter showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view of the water filter of FIG. 1 with a cover removed;

FIG. 9 is a rear elevational view of FIG. 8;

FIG. 10 is a left side elevational view of FIG. 8;

FIG. 11 is a right side elevational view of FIG. 8; and,

FIG. 12 is a top plan view of FIG. 8.
